UNITED STATES PATENT OFFICE.

ROSCOE C. PFLEAGER, OF PHILADELPHIA, PENNSYLVANIA.

LAMP-SOCKET SWITCH.

Patented Feb. 25, 1919.

1,295,588.

Specification of Letters Patent.

Application filed June 1, 1917. Serial No. 172,210.

To all whom it may concern:

Be it known that I, ROSCOE C. PFLEAGER, a citizen of the United States, residing in Philadelphia, Pennsylvania, have invented 5 Lamp-Socket Switches, of which the following is a specification.

One object of this invention is to provide a simple, substantial and relatively inexpensive form of socket switch particularly designed for use in imitation candles, the arrangement of parts being such as to cause the relatively quick making and breaking of the circuit of which said switch constitutes a part.

Another object of the invention is to provide a form of switch constructed for use with a candelabra—or Edison—base socket, and designed for operation by a suitable lever adjacent its lower end.

20 A further object of the invention is to provide a socket switch of the general type indicated which shall have its parts so arranged as to permit free passage of the wires through its body or central stem without requiring the provision or formation of 25 openings in the latter.

It is also desired to provide a switch with a novel form of stem particularly adapted for attachment to a candelabra socket or an 30 Edison socket.

The invention further contemplates a 35 socket switch capable of being operated by the rotation of its movable member in either direction together with such a disposition of the contacts as will cause them to be at all 40 times within closed compartments with a view to preventing short circuiting between said arms or arcing as well as possible leakage of current to the metallic parts of the device.

I also desire to provide a novel arrangement of switch contacts and mountings therefor, particularly adapted for use within an elongated casing structure such as an 45 imitation candle.

These objects and other advantageous ends I secure as hereinafter set forth, reference being had to the accompanying drawings, in which,

50 Figure 1 is a side elevation partly in vertical section, illustrating a switch constructed according to my invention;

Fig. 2 is a vertical section on the line 2—2,

Fig. 1; and

55 Fig. 3 is a detached perspective view illustrating certain of the parts going to make up the preferred form of my switch.

In the above drawings, 1 represents a branch or supporting arm of a lighting fixture which is usually made tubular for the accommodation of a pair of current conductors 2 and 3 and this arm terminates in a boss or head 4 having an externally threaded outlet 5. On this outlet is screwed a coupling member 6 made in the form of an internally threaded sleeve having at one end a hexagonal collar 7 for the reception of a wrench. Threaded into this coupling is a tubular stem 8 likewise threaded at its upper end and having in turn threaded upon it a flanged, internally and externally threaded collar 9.

In the form of my invention shown in the drawings this collar has mounted upon it a tubular stem extension 10 threaded at its upper end for the reception of the threaded stem or plug 11 of a lamp socket 12. Said socket is designed for the reception of an Edison base incandescent lamp 13 and with the switch mechanism hereafter described, 80 the stem, conductors, etc., is designed to be inclosed within a glass tube 14 simulating a candle and said casing, which is usually of white glass, extends from the top of the socket 12 down to a flat annular plate 15 which in the case shown, is rotatably mounted upon a canopy or ornamental metal base structure 16 supported by the head or boss 4 on the tubular fixture branch 1.

Obviously, if desired the stem extension 90 10 may be omitted and the supporting plug 11 of the socket 12 screwed directly into the upper threaded end of the collar 9 or if desired, other forms of socket such as that 95 customarily designed for use in candelabra may be threaded upon or within said collar without departing from my invention;—it being obvious that the inclosing casing or imitation candle would in such case be made of suitable length.

As shown in Fig. 3, the upper end of the tubular stem 8 has two outwardly extending lugs or arms 17 preferably formed by pressing out opposite portions of its structure and these are designed to fit into opposite radial recesses 19 formed in an insulating sleeve 18 so as to immovably hold it on the upper part of said stem below said lugs or arms. At points on the sleeve 18 respectively 90° distant from the slots 19, are 110 formed elongated recesses extending parallel with the longitudinal axis of the structure and designed for the reception of a pair of contact strips 20 and 21. The upper ends of

these strips are provided with binding screws or terminals 22 and their lower ends are laterally extended and curved as indicated at 23 and 24 to form part of or contact 5 form with the wave-shaped lower edge of an enlarged diameter portion 25 of the insulating sleeve 18. These contacts are locked or held in place within their recesses by an insulating ring 26 of the same diameter as 10 the part 25, below which the body of the sleeve 18 extends to provide a support or journal for a rotary insulating sleeve 28.

The lower end of this latter sleeve is made of rectangular section as indicated at 29 and 15 has slidably mounted on it a tube or sleeve 30 of rectangular section normally pressed away from its circular flange 31 by a spring 32 mounted between the bottom of the tube 30 and the lower end of the rectangular part 20 29. This rectangular vertically slidable sleeve 30 passes through a rectangular opening in the operating plate or handle 15 so that it with the sleeve 28 is necessarily rotated when said operating plate is turned. 25 The latter is provided with a handle 33 whereby it may be conveniently manipulated and has soldered or otherwise rigidly connected to it a circular washer 34 of sheet metal which is rotatable upon the sleeve 6 so 30 as to guide and properly position said operating plate 15.

The upper edge of the rotatable insulating sleeve 28 has an outline complementary to that of the lower edge of the part 25 of the 35 sleeve 18;—that is to say, it is made to have a wavy or undulating outline, formed with the same curves as those of the adjacent end of said fixed sleeve. This rotary sleeve has rigidly fixed to it a metallic ring 35 in electrical connection with a pair of contacts 36 and 37 so mounted that their upper faces lie in and constitute part of the undulating top edge of the sleeve 28.

In that form of my invention shown, these 40 coacting edges of the fixed and rotary sleeves each have four similar curved recesses and in the case of the sleeve 18, the two contacts 23 and 24 are mounted at the bottoms of two of these recesses which are oppositely 45 placed. On the other hand, the contacts 36 and 37 are mounted respectively on two opposite elevated or projecting parts of the sleeve 28. Obviously, in one of the positions of the sleeve 28, its contacts 36 and 37 respectively engage the contacts 23 and 24 of the sleeve 18, while when said first sleeve is turned through an angle of substantially 90° in either direction, said contacts 36 and 37 engage a portion of the edge of the enlarged part 25 of the sleeve 18 at the bottoms of two recesses diametrically opposite those having the contacts 23 and 24 and these latter contacts similarly receive a pair of projections of the edge of the sleeve 28 respectively 55 midway between or 90° displaced from the

two projections carrying the contacts 36 and 37.

The two conductors 2 and 3 pass through the supporting arm 1 and the sleeve 8 into the upper part of the latter where they extend out through the openings adjacent the arms or tongues 17. One of said conductors, as 2, is then connected to a binding screw of the contact strip 20, while the other is extended up between the stem extension 16 and the inner wall of the casing 14 to one of the socket terminals 38. A third conductor 39 is likewise extended from the binding screw constituting the terminal of the contact strip 22 and the second terminal 40 of the socket 12. As shown in Figs. 1 and 2, the various contacts 36—37 and 23—24, with their associated contact strips and terminals, are all inclosed within an insulating sleeve 41 of insulating material such as hard fiber which is inwardly flanged at its upper end and has a central opening 42 for the passage of the upper end of the stem 8 and two branch openings 43 and 44 for the passage of the conductors 3 and 39. 90

Assuming that the switch is closed, *i. e.*, that the contacts 36 and 37 are respectively in engagement with the contacts 23 and 24, current is free to flow from the conductor 2 to the terminal 22, through the strip 20 to the contact 23, thence to the contact 36, ring 35, contacts 37 and 24, strip 21 and conductor 39 to the lamp socket terminal 40 and through the lamp. Thence the current flows to the terminal 38 and to the conductor 3, 100 which leads from the device above described and out through the tubular arm 1.

If it be desired to break the circuit of the lamp by opening the switch, the plate 15 is turned by means of the handle or arm 33 through an angle of 90°, and this movement is transmitted to the sleeve 30, thence to the rectangular base portion 29 of the sleeve 28, which is thus likewise turned through an angle of 90°. The various projections of the edge of this sleeve thereupon ride up on and ultimately pass over the projections of the lower edge of the sleeve 18, for which purpose the sleeve 28 is forced to slide downwardly upon the stem 8 against the action of the spring 32. After said projections of this sleeve have passed beyond the highest point of the sleeve 18, said spring acts to move them at a comparatively high rate of speed into the recesses of said second sleeve and in so doing forces the sleeve 28 toward the latter, the parts ultimately coming to rest with the contacts of one sleeve respectively displaced through arcs of 90° from those of the other sleeve. 110

Obviously therefore, the circuit between each pair of coacting contacts is quickly broken and if the movable sleeve 28 is further rotated through an angle of 90°, said circuit is likewise quickly made as the mov- 120

able contacts are brought into engagement with the fixed contacts. It is particularly to be noted that in all cases the coacting contacts are inclosed within chambers having walls of insulating material, which walls are provided by the coacting portions of the sleeves 18 and 28 and the inclosing tube or sleeve 41.

In view of the above described arrangement, the various parts of the switch are protected from injury as well as effectually concealed within the casing 14, being so protected by the insulating structures that the possibility of a leak occurring to any of the metallic parts in connection with the operating handle 33, is practically negligible. Likewise the danger of short circuiting between contacts of different polarity or the production of destructive arcs is practically 20 completely avoided and the structure is so made that there is little likelihood of any of the parts getting out of order or requiring repairs.

I claim:—

25 1. The combination of a supporting member; two sleeves thereon having their adjacent edges of complementary outline, one sleeve being rotatable and longitudinally slideable; two connected contacts on one edge 30 of said movable sleeve; two other contacts on the adjacent edge of the other sleeve; means for yieldingly pressing said sleeves together; a tubular casing inclosing said parts; a rotary actuating member mounted 35 below the casing; and an element connecting the movable sleeve with said actuating member.

2. The combination of a supporting member; two sleeves thereon having their adjacent edges of complementary outline, one sleeve being rotatable and longitudinally slideable; two connected contacts on one edge 40 of said movable sleeve; two other contacts on the adjacent edge of the other sleeve; means for yieldingly pressing said sleeves together; a tubular casing inclosing said parts; a rotary actuating member mounted 45 below the casing; and an element connecting the movable sleeve with said actuating member, consisting of a third sleeve slideable on but non-rotatably fixed to both the movable sleeve and said actuating member.

3. The combination in an electric switch of a supporting structure; a plate rotatably mounted thereon and having an opening of other than circular outline; an insulating body rotatably mounted on the supporting structure above said plate and having a portion fitting the opening thereof; a second insulating body mounted above the first body and fixed to the supporting structure; terminals mounted on the second insulating body; a pair of contacts mounted on the

edge of the latter body adjacent the first insulating body and respectively connected to 65 the terminals; with two other contacts mounted on the first insulating body in position to respectively cooperate with those on the second body.

4. The combination of a tubular supporting structure; an insulating body fixed to said structure; a second insulating body mounted below the first body and rotatable on said supporting structure; two pairs of contacts mounted on the adjacent edges of 70 75 said insulating bodies; a metallic ring mounted on one of the bodies and electrically connecting the contacts thereon; two terminals on the other insulating body respectively connected to its contacts; a spring 80 mounted under the lower and movable insulating body; a projecting arm for turning said latter body; with means for moving it longitudinally of the supporting structure when it is turned. 85

5. The combination in an electric switch of a supporting structure; a metallic plate rotatably mounted thereon and having an opening of other than circular outline; a sleeve non-rotatably fitting the opening of 90 said plate and rotatable therewith; a spring in said sleeve; a body of insulating material non-rotatably fitting the sleeve and longitudinally slideable therein; a relatively fixed body of insulating material mounted above 95 said first body; two pairs of coöperating contacts respectively on the adjacent edges of said insulating bodies; means for electrically connecting the contacts of one pair; terminals respectively connected to the 100 other pair of contacts; and means for causing longitudinal movement of the first body of insulating material when it is turned.

6. The combination in an electric switch of a fixed tubular spindle; two insulating sleeves of which one is fixed to said spindle and the other is rotatable thereon; terminals on said fixed sleeve; contacts also on said sleeve respectively connected to said terminals and mounted on the edge thereof adjacent the second sleeve; a metallic ring on said second sleeve; contacts on the edge of the latter sleeve coacting with the contacts of the fixed sleeve and respectively connected to said ring; a metallic sleeve rotatably mounted on the spindle and connected to the second insulating sleeve to cause rotation thereof while permitting it to slide on the spindle; a spring between said insulating sleeve and the metallic sleeve; and a 110 115 plate including a projecting arm and having an opening nonrotatably receiving the metallic sleeve. 120

In witness whereof I affix my signature.

ROSCOE C. PFLEAGER.
